ELBRIDGE J. STEELE, OF NEW BRITAIN, ASSIGNOR TO TURNER, SEYMOUR & JUDDS, OF WOLCOTTVILLE, CONNECTICUT.

Design No. 4,822, dated April 18, 1871.

DESIGN FOR A DRAWER-PULL.

The Schedule referred to in these Letters Patent and making part of the same.

To all whom it may concern:

Be it known that I, ELBRIDGE J. STEELE, of New Britain, in the county of Hartford and State of Connecticut, have invented and produced a new and original Design for a Drawer-Pull; and the following is declared to be a correct description of the same.

This design relates to the shape given to said drawer-pull, and also to the ornamentation upon the same.

In the drawing—

Figure 1 is an inverted plan of said pull;

Figure 2 is a face view of the same; and

Figure 3 is a cross-section at the line $x x$, fig. 2.

The front portion a of the pull, and the sides $b b$ also, are segments of a hollow cylinder, and said portions $a b b$ are joined by a meter at $c c$.

The lower edge of the portions $a b b$ is formed with an inward-projecting flange, d , and from the sides $b b$ project the ears $e e$ for the screw-holes.

The general outline of said lower edge is a section of an ellipse.

The scroll ornaments $f i i$, upon the front a and sides $b b$, stand in relief upon recessed or sunken panels, ornamented in imitation of lace-work, the narrow bands $h h$ standing in relief and surrounding said recessed portions or panels.

I claim as my invention—

1. The design of the shape and configuration of the drawer-pull, substantially as shown.

2. The design of the ornaments $f i i$ and panels in the exterior curved surface of the drawer-pull, as shown.

Signed by me this 22d day of March, A. D. 1871.

ELBRIDGE J. STEELE.
